HARP

Hans Wallen, San Jose, Calif.

Application September 30, 1937, Serial No. 166,654

5 Claims. (Cl. 84—266)

This invention relates to a harp primarily of the table or Finnish type.

It is generally aimed to provide such a musical instrument of this type capable of more universal use and adaptation to play substantially any kind of music, and particularly to provide for changing the key during the performance.

The more specific objects and advantages will become apparent from a consideration of the description following taken in connection with accompanying drawings illustrating an operative embodiment.

In said drawings:

Figure 1 is a plan view of the harp

15 Figure 2 is a vertical sectional view taken on the line 2—2 of Figure 1;

Figure 3 is a fragmentary longitudinal sectional view taken on the line 3—3 of Figure 1;

20 Figure 4 is a detail longitudinal sectional view taken on the line 4—4 of Figure 1;

Figure 5 is a fragmentary plan view of a portion of the harp with the sound board removed and

25 Figure 6 is a detail section taken on the line 6—6 of Figure 4.

Referring specifically to the drawings wherein like reference characters designate like or similar parts, the harp has a suitably shaped hollow box or casing as at 10, the top of which at 11 constitutes the sound board and has a sound hole 12 therein. Within the box is a sound chamber 13 having a suitably mounted inner sound board 14.

30 Strings of the usual material are provided at 15 over the sound board 11 and five of such strings are connected to each of seven bars 16 at openings or the equivalent, 17 thereof. The other ends of such strings 15 are detachably secured in place by tuning pins 18 frictionally engaged in sockets 19 of a mounting strip 20. An L-shape guard 21 is disposed over the pins 18, the guard being hinged as at 22 to the box or casing 10 in order that it may be swung to expose the pins. The strings cross a keyboard as 40 at 10a to enable the different strings to be easily located.

45 Reverting to the bars 16, they are of L-shape since they have angular arms 23. Such bars are mounted to individually swing on axes transverse to the sound board. To this end, posts 24 rise from a shelf 25 forming part of the casing or box 10. In each post 24, a screw 26 is threaded, whose inner end enters the adjacent end of the bars 16, to form a gimbal or pivot therefor. In 50 addition, and as best seen in Figure 4, each bar

16 at the junction with its arm 23, has a recess or socket 27 into which a lug 28 of a bracket 29, secured to the shelf 25, extends, so as to form a second pivotal support for the bars.

55 Bolts or rods 30 are screw threaded at 31 to the shelf 25 and extend through enlarged slots 32 in the arms 23, beyond which expansive coil springs 33 surround the same and are held adjustably in place by means of nuts 34 screw threaded on the rods 30. Such springs, therefore, maintain the sockets 27 and studs 28 in engagement, serving to prevent displacement of the bars 16, and permitting rocking movement thereof through depression of the arms 23 adjacent their free ends, since clearance is provided as at 35 15 in the shelf 25.

Brackets 36 are provided on the shelf 25 and pivotally mounted therein are studs 37 of tuning buttons or levers 38, one for each of the seven bars. Such buttons 38 remain in any adjusted 20 position since expansive coil springs 39 surround the studs 37, bearing against brackets 36 and cotters or the like 40 on such studs. Buttons 38 have handles as at 41, whereby they may be swung on the axes 37. Said buttons 38 have slots 25 or cutaway portions as at 42 into which reduced extensions 43 of the arms 23 extend. The slots 42 have walls providing cam surfaces engaged by the extensions 43 so that through the rocking of the buttons 38, the arms 23 may be rocked in order to vary the tension of the strings 15 for tuning purposes.

Adjacent the buttons 38 is a detachable plate 44, screws 45 preferably connecting it to the casing 10. Said plate has openings 46 therein for 35 the guidance of the buttons 38.

A wall 47 partly overhangs the strings and mounts an echo stop 48 for the latter.

The buttons 38 correspond to the musical tunes C, D, E, F, G, A and B as indicated in the drawings.

It will be realized that through shifting of the buttons 38 that the key or pitch may be changed. Such shifting of the buttons tensions the strings. Tightening thereof raises a semitone, shifting 45 again in the same direction raises a semitone again. This makes the harp double acting. I find that the harp gives sweet, mellow tones, especially since there is a large air chamber. The 50 harp is so constructed that when the button is vertical, it gives a natural tune, when pushed to one extreme, it makes all the C's sharp in every octave and when pulled to the other extreme makes all the C's flat in every octave.

The present harp is played with the fingers like a concert harp.

Various changes may be resorted to provided they fall within the spirit and scope of the invention.

5 I claim as my invention:

1. In a string adjusting means for a harp or the like, a bar to which the strings at one end are fastened, means pivotally mounting the bar 10 on the soundboard, spring means engaging and urging the bar to normal position, and means operable against the bar to vary its position counter to the urgency of said spring means.

2. In a string adjusting means for a harp or 15 the like, a bar to which the strings at one end are fastened, means pivotally mounting the bar on the soundboard, spring means engaging and urging the bar to normal position, means operable against the bar to swing the bar counter to 20 the urgency of said spring means, said means comprising a rotatable element, said element having a cam surface contacting the bar and movable against the latter.

3. In a string adjusting means for a harp or 25 the like, a bar to which the strings are connected at one end, means on the soundboard pivotally engaging the bar at one end, said bar having a notch, a pivot member on the soundboard engaging the notch, a rod, the bar having an opening enlarged with respect to the rod and through 30 which the rod extends, an expansive coil spring engaging the bar and mounted on said rod, and

an element having a cam movable against the bar to rock the same to adjust the strings.

4. In a string adjusting means for a harp or the like, a bar to which the strings are connected at one end, means on the soundboard pivotally engaging the bar at one end, said bar having a notch, a pivot member on the soundboard engaging the notch, a rod, the bar having an opening enlarged with respect to the rod and through 10 which the rod extends, an expansive coil spring 15 engaging the bar and mounted by said rod, an arm on said bar, an element having a cam surface engageable with the arm to shift the same to rock the bar, means pivotally mounting the arm, and friction means to maintain the arm in different adjusted positions.

5. In a string adjusting means for a harp or the like, a bar to which the strings are connected at one end, means on the soundboard pivotally engaging the bar at one end, said bar having a notch, a pivot member engaging the notch, a rod, the bar having an opening enlarged with respect to the rod and through which the rod extends, an expansive coil spring 20 engaging the bar and mounted by said rod, an arm on said bar, an element having a cam surface engageable with the arm to shift the same to rock the bar, means pivotally mounting the arm, friction means to maintain the arm in different adjusted positions, the cam having a slot, one wall of which constitutes the cam, said arm extending into said 25 slot.

HANS WALLEN.
